UNITED STATES PATENT OFFICE.

FRANK C. DE REAMER, OF SCHENECTADY, NEW YORK, ASSIGNOR TO GENERAL ELECTRIC COMPANY, A CORPORATION OF NEW YORK.

CORD CONNECTER.

Application filed January 10, 1921. Serial No. 436,073.

To all whom it may concern:

Be it known that I, FRANK C. DE REAMER, a citizen of the United States, residing at Schenectady, in the county of Schenectady, 5 State of New York, have invented certain new and useful Improvements in Cord Connecters, of which the following is a specification.

The present invention relates to cord connectors and has for its object to provide an improved structure and arrangement in a device of this character.

For a consideration of what I believe to be novel and my invention, attention is directed to the accompanying description and the claims appended thereto.

In the drawing, Fig. 1 is a side elevation of a cord connector embodying my invention; Fig. 2 is a view of the connector, the 10 mounting blocks on one side being removed to show the interior of the connector; Fig. 3 is a longitudinal sectional view, the mounting blocks being shown separated; Fig. 4 is an exploded view of the parts which go 15 to make up the plug member of the connector; Fig. 5 is a similar view of the parts which go to make up the receptacle member of the connector; Fig. 6 is an enlarged perspective view of a connector showing 20 the manner of connecting a lead thereto, and Fig. 7 is a perspective view of a modification.

Referring first to the plug member of the connector, it comprises two mounting blocks 10 and 11 which when assembled one on the other form the casing of the plug. Blocks 10 and 11 are made of suitable insulating material by moulding or otherwise, and are preferably exactly alike and 25 interchangeable. In other words, each forms one-half the casing. One of the blocks, as block 10, is shown in perspective in Fig. 4 and it will be understood that the other block 11 is preferably exactly like it. Referring particularly to Fig. 4, the block 30 comprises a flat piece of material tapered at one end to form a semi-circular neck 12 having a groove 13 which forms one-half the circular opening through which the cord enters the plug. Groove 13 opens into two chambers 14 separated by a wall 15. In the bottoms of chambers 14 are recesses 16 to accommodate the insulation on the cord. The other end of the block is flat and at 35 such end are two spaced rectangular slots

17 which extend from the end of the block to chambers 14. Extending transversely of slots 17 at their bottoms are projections 18 preferably semi-circular in cross-section and formed as an integral part of the block, 60 and in the block between slots 17 is a hole 19 for the reception of a clamping screw. The end of wall 15 adjacent neck 12 is enlarged to form a head 20 through which is a hole 21 for the reception of a second clamping screw. The outer ends of holes 19 and 21 are countersunk to receive the heads and 65 nuts of the clamping screws so they will be flush with the surfaces of the plug. The countersunk portion of the openings are all 70 of the same contour as the nuts, for example hexagonal, so the screw may be put through the blocks either way and the blocks be exactly alike and interchangeable.

Each contact 22 of the plug comprises 75 a straight flat strip of metal of suitable thickness having an opening 23 at its outer end and a post 24 at the inner end. Post 24 may be fastened to the strip in any suitable manner, it being shown in the present 80 instance as having a reduced end which passes through an opening in the strip and is riveted or flanged over. The end of the strip and the post are provided with a tapped opening 24' to receive a binding screw 85 25 which screws into the tapped opening from the side of the strip opposite to that from which post 24 projects. On the end of contact 22 just beyond the head of binding screw 25 are two spaced projections 26, 90 which are preferably formed by upsetting the end of the strip and which serve as flanges to hold the wire under the head of the screw. In the edges of the contact strip between its ends are notches 27 in which 95 projections 18 fit when the plug is assembled.

A complete plug comprises two mounting blocks and two contacts as shown in Fig. 2, and two clamping screws 28 with nuts 29 as shown in Fig. 3, and is assembled 100 in connection with a cord as follows:

A usual form of cord as indicated at 30 has the outside insulation 31 removed for a suitable distance at the end to expose the two lead wires 32, and the insulation is then 105 removed from the ends of wires 32 to expose the bare wire 33 for a sufficient length to wrap around binding screws 25. Each lead wire is then fastened to a contact strip 22, the portion of the wire from which the in-

sulation has not been removed being given a turn around post 24 after which the bare end of the wire is brought across the end of strip 22, bent in between projections 26, given one or more turns around binding screw 25, and the binding screw then screwed down. This is well illustrated in Fig. 6. After a contact strip has been thus fastened to each lead wire, the two contact strips are laid one in each slot 17 of a mounting block as shown in Figs. 2 and 3, the location being such that projections 18 lie in notches 27. A second mounting block is then placed on top the block in which the contact strips have been placed so its projections 18 fit in notches 27 in the exposed half of the strips and the two blocks are then fastened together by the clamping screws 28 and nuts 29.

The width of slots 17 is about the same as the thickness of strips 22 and the depth of slots 17 is made approximately equal to one-half the width of strips 22. Also the length of slots 17 is sufficient to give good lateral support to the contact strips. As a result when the two mounting blocks are fastened together the contact strips are held parallel to each other and absolutely prevented from twisting or moving laterally.

The bottoms of slots 17 are flush with the bottoms of chambers 14 so the entire lengths of strips 22 within the blocks are in engagement along their edges with the blocks and firmly clamped by them. This gives a long seating for the contact strips and prevents them from tilting edgewise. The engagement of projections 18 in notches 27 in the two edges of the contact strips holds the contact strips against axial movement. It will thus be seen that although the contact strips comprise only straight flat strips of metal they are firmly anchored in the mounting blocks and can neither move out of their exact parallel positions nor come out.

The purpose of posts 24 is to form a strain reliever for the wire connections with binding screws 25. It is to be particularly noted that these strain relieving posts are carried by the contact strips themselves and form in substance an integral part of them and that the binding screws thread into such posts. This results in a very simple arrangement, which while performing its intended function in a most efficient manner at the same time can be provided at a low cost and adds no difficulties in the way of assembling. Furthermore such posts are most advantageous for receiving the binding screws. The projections 26 serve to hold the lead wires from slipping sidewise off the ends of the contact strips, and to also hold them under the binding screws when they are being screwed down. As will be clear from Fig. 2, the contact strips 22 are assembled in the mounting blocks with the

binding screw heads adjacent to partition wall 15. This brings the strain relieving posts 24 over recesses 16 which serve to accommodate the insulation of lead wires 32. In this connection it will be noted that recesses 16 are to one side of the contact strips 22 so as not to interfere with the seating of the edges of the strips on the bottoms of chambers 14. When a lead wire is connected to the plug as shown in Fig. 2 and the two mounting blocks are clamped together any pull on the cord will be taken by posts 24 thereby protecting the connections with the binding screws 25.

The receptacle embodies the same general structural features as the plug, and the same reference numerals with the exponent "a" added are applied to corresponding parts. It comprises two mounting blocks 10^a and 11^a of insulating material each alike and when assembled one on the other forming the casing of the plug. One of these blocks, for example, block 10^a, is shown in perspective in Fig. 5 and it will be understood that the other block 11^a is like it. Referring particularly to Fig. 5, the block comprises a flat piece of material tapered at one end to form a semi-circular neck 12^a having a groove 13^a which forms one-half of the circular opening through which the cord enters the plug. Groove 13^a opens into two chambers 14^a separated by a wall 15^a and in the bottom of chambers 14^a are recesses 16^a to accommodate the insulation on the cord. The other end of the block is flat and at such end are two spaced rectangular slots 17^a which extend from the end of the block to chambers 14^a. Slots 17^a are longer and wider than slots 17 of the plug and are provided with projections 18^a which extend part way across them. In the outer side walls of chambers 14^a are notches 14^b which serve to accommodate the ends of the binding posts. The block is provided with a hole 19^a, and a head 20^a through which is a hole 21^a for the reception of clamping screws. The outer ends of holes 19^a and 21^a are countersunk to receive the heads and nuts of the clamping screws in the same manner as are holes 19 and 21 of the plug.

Each contact 22^a of the receptacle comprises a flat strip of metal which may be of less thickness than contact strips 22 and which has its outer end bent back upon itself to form a spring contact piece 22^b in which is struck out a head 23^a adapted to engage in an opening 23 in a contact strip 22 of the plug. At the elbow of the bend the material is pressed inward as indicated at 23^b to form a reinforcing and strengthening rib over which spring contact piece 22^b bends. This rib serves to prevent further permanent bending of spring contact piece 22^b and to insure that it maintains its spring. At the inner end of contact strip 130

22^a is fixed a post 24^a having a tapped opening 24^a to receive a binding screw 25^a. Post 24^a may be fastened to contact strip 22^a in the same manner as post 24 is fastened to contact strip 22. In the case of post 24^a, binding screw 25^a screws into it to form its outer end so that instead of forming projections on contact strips 22^a, corresponding to projections 26 of contact strip 22, the outer end of post 25^a is provided with a flange 26^a which receives the head of binding screw 25^a. In flange 26^a is a notch 26^b through which the lead wire extends. Flange 26^a performs the same function as do projections 26. In the edges of contact strips 22^a are notches 27^a in which projections 18^a fit when the receptacle is assembled.

A complete receptacle comprises two mounting blocks and two contacts as shown in Fig. 5 and two clamping screws 28^a with nuts 29^a as shown in Fig. 3. It is assembled in connection with a cord in a manner similar to that of the plug already described, corresponding parts performing similar functions, and as will be readily understood contact strips 22^a will be firmly anchored between mounting blocks 10^a and 11^a and posts 24^a will serve as strain relievers for the connections. Slots 17^a are of the same depth as slots 17 and are of sufficient width to allow of the insertion of the outer ends of contact strips 22 into them in the well understood manner to make engagement with contact strips 22^a. This is well illustrated in Fig. 2. When the plug and receptacle are connected in this manner they are held together by the pressure of spring contact piece 22^b and by bead 23^a engaging opening 23.

In the case of both the plug and the receptacle it will be seen that they are formed of few parts which can be manufactured at a low cost and easily assembled. Or, if found desirable, the parts which go to make up the plug and receptacle, comprising in each case only three different kinds, viz., the mounting blocks, contacts, and clamping screws, may be shipped unassembled and be assembled as used. The only tool required for assembling is an ordinary screw driver and the work of assembling can be done by ordinary workmen. It is particularly to be noted that no screws are used in assembling the contact strips in the mounting blocks.

Because of their simple structure the plug and receptacle are well adapted to be made in miniature sizes which is very desirable for certain applications. The fact that the strain relieving posts form an integral part of and are carried by the contact strips is a feature of particular importance in the matter of miniature sizes as it means that

the strain relieving posts occupy the minimum of space.

In Fig. 7 I have shown a modification wherein the slots 39 of mounting block 40, corresponding to slots 17 and 17^a of Figs. 4 and 5, instead of being provided with projections as 18 or 18^a are provided with depressions or recesses 41 of suitable depth and length and of a width equal to the thickness of the contact strips. Depressions or recesses 41 are formed adjacent the outside wall of slots 40. The contact strips 42 instead of being formed with notches such as 27 or 27^a of Figs. 4 and 5 are provided with wings or projections 43 adapted to fit in depressions or recesses 41. Otherwise the arrangement of Fig. 7 is in substance the same as that already described except that the mounting block 40 is shown of a type for a series connector. The specific arrangement of Fig. 7 has the advantage that the wings or projections 43 are strong and not likely to break. They also serve not only to position the contacts to hold them from axial movement but also to hold them from transverse movement in case the bent contact ends should take a further permanent bend.

It will be understood of course that while I have shown a plug and receptacle, each embodying features of my invention and going to make up a cord connector, either the plug or receptacle may be used with a receptacle or plug or other structure if found desirable.

In accordance with the provisions of the patent statutes, I have described the principle of operation of my invention, together with the apparatus which I now consider to represent the best embodiment thereof, but I desire to have it understood that the apparatus shown is only illustrative, and that the invention may be carried out by other means.

What I claim as new and desire to secure by Letters Patent of the United States, is:—

1. A cord connector member comprising two mounting blocks of insulating material clamped together to form a casing, said blocks having grooves which register to form an opening for a conductor cord at one end of the casing and a plurality of spaced parallel grooves which register to form a holding means for connecting contacts at the opposite end of the casing, said contacts comprising flat straight strips of conducting material mounted edgewise in said last-named grooves and projecting exteriorly of the casing, said last-named grooves for a portion of their length having a width substantially equal to the thickness of the contact strips whereby the strips are held from twisting, interengaging parts carried by the edges of the contact strips and the

- bottoms of the grooves for holding said strips from longitudinal movement, a strain relief post for a conductor wire mounted on each contact strip adjacent its inner end to 50
5 project laterally from one face thereof and a binding screw for said conductor wire, which screw passes through the contact strip from the opposite face thereof into the strain relief post, said strain relief post being 55
10 threaded to receive said screw.
2. A connector member comprising two mounting blocks clamped together and provided with grooves at one end which form an opening for the reception of a cord and a 60
15 plurality of spaced grooves at the other end, flat straight contact strips located edgewise in said last-named grooves, said last-named grooves for a portion of their length having a width substantially equal to the thickness 65
20 of the contact strips, whereby they serve to hold such strips from twisting, and inter-engaging parts carried by the edges of the contact strips and the bottoms of said 70
25 grooves which parts serve to hold the contact strips from longitudinal movement.
3. A connector member comprising two mounting blocks clamped together and provided with grooves at one end which form an opening for the reception of a cord and a 75
30 plurality of spaced grooves at the other end, flat straight contact strips located edgewise in said last-named grooves, notches located in the edges of said contact strips midway 80
35 between their ends, and projections located in the bottoms of said grooves interlocking 85
40 with said notches to hold the contact strips from longitudinal movement.
4. A connector member comprising two mounting blocks, means fastening them together, said blocks having a cord opening at one end and a plurality of spaced grooves at the other end, a flat contact strip clamped between the blocks edgewise in each groove, a strain relieving post for a cord mounted on 90
45 each contact strip and projecting laterally from it, a binding screw for a wire held in said post, and interengaging parts car-
- ried by the edges of each contact strip and the bottoms of said grooves which parts serve to hold each contact strip from longitudinal movement. 50
5. A contact strip for a connector member, said strip being flat, straight and of one piece, a strain relieving post for a cord projecting laterally from it at one end and 55
provided with a threaded opening, and a binding screw for a wire in said threaded opening.
6. A contact strip for a connector member, said strip having a strain relieving post at 60 one end around which a cord may be wrapped, a binding screw which screws into said post, and projecting means adjacent the head of the screw for holding a wire under it. 65
7. A contact strip for a connector member, said strip having a strain relieving post at one end around which a cord may be wrapped, a binding screw which screws into said post and projecting means adjacent the head of the screw for holding a wire 70 under it, said strip having notches in its edges.
8. A contact strip for a connector member, said strip having one end bent back upon itself to form a spring contact, a strain relieving post at the other end of said strip, and a binding screw in said post. 75
9. A contact strip for a connector member, said strip having one end bent back upon itself to form a spring contact, a strain relieving post at the other end of said strip, a binding screw in said post, and a flange on the post which surrounds the head of the screw. 80
10. A contact strip for a connector member, said strip having a strain relieving post at one end around which a cord may be wrapped, a binding screw which screws into said post, and projections on the edges of said strip intermediate its ends. 90

In witness whereof, I have hereunto set my hand this 8th day of January, 1920.

FRANK C. DE REAMER.
